UNITED STATES PATENT OFFICE

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

APPARATUS FOR TREATING PETROLEUM

Original application filed January 2, 1920, Serial No. 348,789. Divided and this application filed September 6, 1921, Serial No. 498,888. Renewed May 28, 1928.

This application is a division of Serial No. 348,789, filed January 2, 1920 by me.

This invention relates to an apparatus for treating petroleum and particularly relates 5 to an apparatus in which the boiling points of petroleum treated are materially reduced.

The objects of the invention are to provide an apparatus wherein petroleum is subjected to heat and pressure, the vaporized portion 10 being permanently separated from the un- vaporized portion; to provide an apparatus whereby the generated vapors are subjected to progressive cooling and condensation; the heavier portions being revaporized while the 15 lighter portions are collected separately; to provide an apparatus whereby only the raw oil fed into the apparatus and the heavy condensate from the vapors generated are subjected to the action of heat and pressure; to provide an apparatus whereby the petroleum to be treated is passed through 20 the heating tubes but once, the vaporized portions being subjected to a partial condensation, and while undergoing said condensation, being mixed with, and the condensation materially assisted by a continuous supply of raw material, the mixture being automatically fed to the heating tubes where it is subjected to a further heat treatment.

30 The single figure in the drawing is a side elevation of the apparatus used in carrying out the process with parts broken away and shown in section. Any arrangement of apparatus suitable for carrying out the principle, 35 as set forth in my invention, may be used, as I claim the broad principles set forth and claimed in this application.

Referring to the drawing, A is the furnace proper which is shown in the drawing provided for burning coal. It may be designed 40 for burning natural gas, oil or any other fuel. A-1 is a stack. The still in which the oil is heated and vaporized consists of tubes B2, which are connected to lower chambers B' and B'' and an upper chamber B, the tubes B2 being positioned in the furnace A. The oil 45 passes from chamber B' up through the tubes at the left of the baffle into the chamber B. The oil passes from the chamber B down the tubes at the right of the baffle D3 into the

chamber B''. The vapors pass into the drum B. C is a vapor line connecting the chamber B to the dephlegmator D. This dephlegmator has an open compartment at the bottom marked D-1. The space above same is filled with broken material marked D-2 to act as a baffle and yet leave sufficient voids for the vapors to percolate up through same. A space in the dephlegmator D is left above the broken material D-2. E is a vapor line connecting the dephlegmator D to the condensing coils E-1, located in the condensing box E-2 and which coil connects by line E-3 the receiving tank F. G is a pipe connecting with source (not shown) for supplying the pump G-1 with raw material. G-2 is the discharge line from pump G-1 into the top of dephlegmator D. H is a line extending from the bottom of the dephlegmator D to the chamber B-1. J is a drawoff connecting with the drum B''. K is a liquid level gauge having valves K-1 condensing coil K-2, positioned in tank K-3, which is maintained full of water. L are pressure gauges. M designate temperature 55 gauges. N is pressure safety valve. P is a manhole opening. R, R-1, R-2 and R-3 are valves. S is liquid level gauge. T is the gas outlet from tank F and T-1 is liquid drawoff from tank F. U is a check valve and Z are supports for the different parts of the apparatus.

The following illustrative run of the process may be given: Gas oil of 32° Baumé gravity from, say, a Kansas field, is pumped from any suitable source of supply through line G and pump G-1 to the upper end of the dephlegmator D, and passes through the broken up stone D2 and the perforated partition into the chamber D-1; thence through the line H 60 into compartment B-1 up through the tubes to the left of the baffle into the chamber B. The oil circulates down through the vertical tubes to the right of the baffle into chamber B'' and thence out through line J, controlled by valve R to a suitable residue tank. The vapors pass out through line C into the dephlegmator D-2 and thence to the condenser E-1 and receiver F. A pressure of, say, 135 lbs. may be maintained on the entire system 65 70 75 80 85 90 95 100

through controlling the valves R, R-1 and R-2. This process will convert 50 percent of said gas oil into 50 degree Baumé gravity pressure distillate, 65 percent of which pressure distillate will be gasoline of 58 degree Baumé gravity and low boiling point.

I claim as my invention:

1. In an apparatus of the character described, the combination with a furnace, of a plurality of vertical tubes connecting an upper drum, and a plurality of lower drums, said tubes extending through the furnace, of a dephlegmator connected with the upper drum, said dephlegmator having a perforated plate therein for supporting broken material, means for taking off vapors from the upper part of said dephlegmator, and condensing and collecting them, means for supplying raw oil to the upper portion of the dephlegmator, and for forcing the same downwardly through said broken material to assist the condensation of the vapors passing up through the dephlegmator and to preheat the oil, means for passing reflux condensate and fresh oil from said dephlegmator to one of said lower drums, means for withdrawing residue from another of said lower drums, and means for maintaining the system under superatmospheric pressure.
2. In an oil cracking apparatus, the combination with a plurality of vertical tubes arranged in a cylindrical formation between an upper drum and a plurality of lower drums, said tubes extending through a furnace, of a dividing wall in said furnace for directing heating gases longitudinally of the tubes, a vapor outlet connected to said upper drum, and a dephlegmator connected to the vapor outlet pipe from said upper drum, means for introducing raw oil to said dephlegmator, means for passing mixed raw oil and reflux condensate from said dephlegmator to one of said lower drums, means for withdrawing residue from another of said lower drums, condensing and collecting means connected with said dephlegmator, and means for maintaining a regulated pressure on the system.
